UNITED STATES PATENT OFFICE.

EMILE FRANCKAERTS, OF SAN FRANCISCO, CALIFORNIA.

DOOR-HOLDER.

1,100,475.

Specification of Letters Patent. Patented June 16, 1914.

Application filed October 6, 1913. Serial No. 793,717.

To all whom it may concern:

Be it known that I, EMILE FRANCKAERTS, a citizen of the United States, and a resident of San Francisco, in the county of San Francisco and State of California, have made certain new and useful Improvements in Door-Holders, of which the following is a specification.

My invention relates to improvements in door holders, and it consists in the combinations, constructions and arrangements herein described and claimed.

An object of my invention is to provide a device for holding a door in open position, which may be readily set or released at will.

A further object of my invention is to provide means for positively holding a door in open position so as to prevent the closing of the same even when considerable force is used, but which will instantly release when a release mechanism is operated, so as to permit the door to close.

A further object of my invention is to provide a door holder having comparatively few parts for accomplishing the above named objects, which is cheaply manufactured, and which is not liable to easily get out of order.

Other objects and advantages will appear in the following specification and the novel features of the device will be particularly pointed out in the appended claim.

My invention is illustrated in the accompanying drawing forming a part of this application, in which—

Figure 1 is a face view of the door holder as applied to a door. Fig. 2 is a sectional view through the door and the door holder. Fig. 3 is a rear view of the door holder. Fig. 4 is a sectional view along the line 4—4 of Fig. 2, and Fig. 5 is a sectional view along the line 5—5 of Fig. 2.

In carrying out my invention I provide a main casing 1, which is of the shape shown in the drawings. It is provided with an upper extended portion 2 and with side lugs 3. The portions 2 and 3 are perforated so as to afford means for attaching the casing to a door.

Arranged to slide within the casing 1 is an auxiliary casing 4, which is hollow. The rear side of the inner casing 4 is provided with a bearing member 5 having an elongated opening 6. The bearing member 5 is dove-tailed as shown in Figs. 4 and 5, to enter the grooves 1^x of the main casing.

This provides means for guiding the inner casing in its movement.

Pivotedly supported at the lower end of the inner casing is a stop member 7, which bears at its lower end a resilient buffer 8 of rubber or other suitable material. The upper end of the stop member 7 is pressed upon by a spring 9, which bears on the inner side of the member 5. The stop 8^x holds the buffer 8 in position.

Arranged to extend transversely of the device are two partitions, a lower one 10 and an upper one 11. These partitions are of the shape shown in Fig. 5. They are provided with central openings arranged to receive a rod 12, which is secured to a cap member 13 at the top of the auxiliary casing 4. The cap 13 is provided with a tongue 13^x arranged to enter a slot in the rear part of the casing 4 and is held in position by means of a screw 14. A spiral spring 15 bears at one end on the cap 13, and at the other end of the partition 11.

A locking member 16 like that shown in Fig. 4 has a tongue 16^a which passes through the slot in the member 5 and enters an opening in a plate 17 secured to the rear side of the casing 1. The plate 17 is also provided with openings arranged to receive one end of the partitions 10 and 11. The locking member 16 passes through an opening in the casings 1 and 4, and is provided with an integral extension 16^b on the outside thereof. The rod 12 passes through an opening 16^c in the locking member 16. A spring 18 normally holds the locking member 16 in such position as to cause the rod 12 to bind against the walls of the opening 16^c. The opening 16^c in the locking member 16 may, however, be brought into position so as to permit a free movement of the rod by moving the locking member 16 downwardly.

From the foregoing description of the various parts of the device the operation thereof may be readily understood. The apparatus is fastened on to the side of the door near the bottom thereof, as shown in Fig. 2. Now when it is desired to open the door and hold it open, one may place his foot on top of the cap 13 and press downwardly. This causes the casing 4 to slide downwardly within the casing 1, spring 15 being put under tension. The locking member 16 is held by the spring 18 so as to prevent the retraction of the rod 12. Thus the stop member 7 is held in close engagement with the floor,

the rubber buffer preventing the movement of the door. If there is any attempt to move the door, the stop member will swing outwardly into the position shown in dotted lines, causing a firmer grip of the device on the floor. The stop member will thus resist any tendency to close the door. Now when it is desired to release the door, the extension 16^b of the locking member 16 is pressed 10 downwardly either with the foot or with the finger, thereby releasing the rod 12, which under the influence of the spring 15, raises the slidable casing 4, together with the stop member 7 from the floor into the position shown in Fig. 2, thereby permitting the door to swing free.

I claim:—

20 In a door holder, a main outer casing provided with grooves, an auxiliary casing disposed within said auxiliary casing and slideable with respect thereto, a bearing member arranged to enter the grooves for guiding the inner casing in its movement, a pivoted

stop member supported at the lower end of the inner casing, a spring having one end 25 normally pressing upon the upper end of the stop member, and the other end bearing on the inner side of the bearing member, a pair of partitions having alined openings, a central clamping member disposed between the 30 partitions and being provided with an opening, a rod carried by the inner auxiliary casing and arranged to extend through the alined openings of the partitions and the central clamping member, the clamping member being movable to grip the rod, the upper end of the spring bearing on the inner auxiliary casing and the lower end bearing on one of said partitions, and a second spring disposed about the rod, one end bearing 35 on the clamping member and the other end bearing on the other of said partitions.

EMILE FRANCKAERTS.
